UNITED STATES PATENT OFFICE.

WALLACE W. GYLLENBERG, OF DETROIT, MICHIGAN.

PRINTING CHART.

Application filed September 12, 1927. Serial No. 218,910.

My invention relates to an improved chart for printing.

The object is to provide a chart for the use of a printer, author, advertising or layout man, etc. whereby one may readily ascertain the amount of space required to print a given amount of typewritten matter in a given style and point of type or whereby one having a given amount of space available for printing 10 and a given quantity of typewritten matter to be printed may readily and quickly ascertain the style and point of type best suited for the purpose.

Heretofore this has been accomplished generally through what might be termed a cut and try method of procedure involving more or less uncertainty and inaccuracy. The material to be printed was measured, the available space was ascertained and then, working 20 with the known number of average characters, the result was sought. Such a method was unsatisfactory. It was laborious, slow and inaccurate. Printing characters vary in width in the same style and point of type and there 25 is, of course, a wide variation between styles and points of type.

My improved chart materially facilitates the performance of this work and lends itself to the accomplishment thereof with a minimum 30 amount of labor and in a minimum amount of time.

The various meritorious features, advantages and objects of my invention will more fully appear from the following description 35 of the embodiment illustrated in the accompanying drawing and defined in the appended claims.

The figure of the drawing is a front elevation of a chart embodying my invention.

My improved chart has a face upon which vertical parallel lines indicate a pica chart 6" in width, there being six pica lines to the inch. At the top and bottom these pica lines are numbered.

I have arranged printed matter upon this chart extending there across, which printed matter is assembled in groups, each group being in a particular style of type. Reading from top to bottom the groups represent the following styles of type: Caslon Old Style, Modern, Bookman, Goudy Bold and Caslon Bold. These groups constitute merely a limited number of the styles of type employed in printing and a working embodiment of my invention would preferably comprise all the

styles of type commonly used by printers in the trade.

Each group comprises successive lines of type in different point sizes. For example, the first group, Caslon Old Style, is the uppermost line printed in six point type and the other lines in the group, reading from top to bottom, are printed in 8, 10, 12, 14, and 18 point type respectively. The other groups with their respective lines of type are like- 60 wise similarly arranged. In my chart adapted for use the different group styles of type would, of course, contain lines representative of the several point sizes. 65

It will be seen that each line in each group has associated therewith numerals, which numerals are here shown arranged at the pica intervals underneath the line. These numerals indicate the average number of printing characters of such style and point of type in 70 a line of the pica length indicated by the numeral. For example, the six point line in the first group, Caslon Old Style, carries the numeral 150 at the end of the line which indicates that there are 150 characters in an average six inch line of this style and point of type, a character being a letter or space interval. This does not mean that necessarily 75 there are 150 characters in this particular line there set up, as printing type varies in width, 80 but that there are 150 characters in an average line. This number has been arrived at by a series of computations based upon an examination of a large amount of printed matter. The other numerals underlying the same 85 line at different intervals indicate the number of characters appearing in an average line of such length. 90

At the bottom of the chart I have shown two lines of typewritten matter, the upper 95 line being elite type and the lower line in pica type. These two lines represent the two well known varieties of typewriter type. Typewriter type does not vary in width and the numerals which are associated with these 100 lines indicate the number of characters in a line of typewriter type of the particular variety indicated of the length shown and it will be seen that there are sixty characters in the six inch line of pica typewriter type and sev- 105 enty-two characters in the same length line of elite typewriter type.

The chart is usable in many ways. If a person has a quantity of typewritten material which it is desired to set up in a given 110

style and point of printing type, it is readily possible to ascertain the required space by placing a line of the typewritten material to be printed underneath the typewritten line on the chart of the same kind of typewriter type and if an average line of the typewritten material to be printed terminates at the numeral 40 on the chart and if it is desired to print this matter in six point Caslon Bold type, it would incidentally appear that a two inch space would be required to print this line in this style and point of type.

On the other hand, if there were a given amount of space available for printing and a given quantity of typewritten material to be printed, it would be as easily possible to ascertain the style and point of type best adaptable for employment to print such typewritten material to fill the available space.

20 Furthermore, one might desire to have the printed matter arranged in a column of a different length, say three inches, in a different style and point of type, for example, Modern eight point, in which event the chart 25 would indicate that an average line would contain fifty-seven characters. The typewriter might then be set to run fifty-seven characters to the line in which case the number of lines of typewritten matter would 30 equal approximately the number of lines of printed matter.

What I claim is:

1. A chart for printing having on its face a plurality of parallel vertical lines equally spaced apart according to a determined interval, successive lines of printed matter arranged thereacross, each line of printed matter being in a given point and style of type, figures associated with each line of printed matter where traversed by said vertical lines indicating the number of printed characters of such point and style of type in an average line or portion thereof of such length and of the same point and style of type; two lines 45 of typewritten matter, one elite and the other pica, likewise arranged on such chart and having associated with each line of typewritten matter where traversed by said vertical lines, figures indicating the number of characters of such variety of typewriter type in a line or portion thereof of that length.

2. A chart for printing having on its face a plurality of parallel defined spaces of uniform width, printed matter of a given style 55 of type arranged transversely over the spaces in successive lines each line being in a given point of type, figures associated with each line of printed matter at determined intervals indicating the number of characters in an average line of printed matter of such point

and style of type of the length indicated, and a line of typewritten matter arranged on such chart having figures associated therewith at the same determined intervals indicating the number of characters in a line of typewritten matter of such kind of the same length. 65

3. A chart for printing having arranged on its face successive lines of printed matter of different form and size of type, numerals associated with each line at determined intervals indicating the number of printed characters in such style and point of type in an average line of printed matter of the length of the interval indicated by the numeral, said chart also having arranged on its face a line of typewritten matter of a determined kind and associated therewith at the same determined intervals, numerals indicating the number of characters of such kind of typewriter type in an average line of the 75 length of the interval indicated by the numeral. 70

4. A chart for printing having arranged on its face a plurality of sets of characters representing different styles and points of 80 printing type and a numeral associated with the type of each style and point indicating the number of characters of such style and point in an average line of a given length. 85

5. A chart for printing having arranged on its face a plurality of groups of printed characters, each group representing a different style of printing type and including 90 printed characters in such style arranged in the various point sizes, and a numeral associated with the characters of each point size in each style group indicating the number of characters of such point and style in an average line thereof in a given pica length. 95

6. A chart for printing having arranged on its face a plurality of groups of printed characters, each group representing a different style of printing type and including successive lines of printed characters in such style arranged in the various point sizes, a different size in each line and a numeral associated with each line in each group indicating the number of characters of such point and style in an average line thereof of a given pica length, said chart also provided with two groups of typewritten characters representing the two varieties of typewriter type, each group having associated therewith a numeral indicating the number of typewritten characters of such variety in a pica line of the same length. 100 110 115

In testimony whereof, I, WALLACE W. GYLLENBERG, sign this specification.

WALLACE W. GYLLENBERG.
